UNITED STATES PATENT OFFICE.

AUGUST W. CORDES, OF NEW YORK, N. Y.

DRAFT-CHECKING DEVICE.

1,327,653.

Specification of Letters Patent. Patented Jan. 13, 1920.

Application filed May 14, 1915. Serial No. 27,977.

To all whom it may concern:

Be it known that I, AUGUST W. CORDES, a citizen of the United States, and resident of the borough of Manhattan, city, county, 5 and State of New York, have invented certain new and useful Improvements in Draft-Checking Devices, of which the following is a specification.

My invention relates to draft checking devices more particularly adapted for use in the construction of buildings and the like and has for its object to provide a device which will at all times assure an air tight and weatherproof joint between units of 10 similar or different materials under all conditions. My improvement particularly contemplates avoiding the necessity for calking the joints which is unsatisfactory at best and must be continually renewed from time to 15 time as physical changes in the units or in the calking takes place. A further object of my invention is to construct my device in its various forms in such a manner that the same may be readily applied in operative 20 position as the construction of the building or the like proceeds. The construction and arrangement of my improvement will be clearly set forth in the description herein- 25 after and the features of novelty thereof will be pointed out in the appended claim.

Reference is to be had to the accompanying drawing which shows a sectional view illustrating an example of my invention.

As shown in the drawing the device comprises a sheet of metal or other material which 35 is shaped to form a main section 11^c and an edge member 14^a extending at an angle to the main section. The edge member 14^a depends from the section 11^c and is turned back at its 40 free edge as shown to form the flange 16^b which if desired may also be provided with teeth along its free edge.

In using this type of my improvement for instance in combination with a brick wall 45 and a door, window or other casing, the frame or casing 17^c which is preferably formed with a groove 18^b extending for instance lengthwise thereof is set up and secured in its intended position by means of 50 temporary stays or braces in the usual manner. The device shown may then be combined therewith by inserting the member 14^a into the groove 18^b with the flange 16^b pointed outward at an angle and in engage-

ment with a wall of the groove 18^b, it being 55 understood that the width of the latter is less than the cross-sectional width of said flange 16^b. Any attempt to withdraw the member 14^a from the groove 18^b by exerting a pull in an outward direction will cause said 60 flange 16^b to bite into said wall of the groove whereby said device is firmly connected with the door frame as will be clearly apparent. The wall 19^b is now built up in proper relation to the frame in the usual way, the projecting section 11^c extending into a mortar joint 20^b between two courses of brick. 65

In order that the said member 11^c may move freely relatively to the joint 20^b the inner end thereof is covered with a covering 70 of impregnated felt or other material 22 which engages opposite surfaces of said section and preferably forms an air space 23 and whereby said section is lubricated as it were. It will be understood that the covering 75 22 comprises a material which remains pliable, such as suitably impregnated felt, plastic slate composition or asphalt composition.

The device is simple in construction, is 80 readily applied and does away entirely with the necessity for calking the joints, thus saving labor and expense and at the same time producing more uniform and effective results. The device also will not injure the 85 units with which it is combined, and will not tear out portions of the mortar joints or of coalescent material if used in connection, for instance, with a wall of concrete.

Various changes in the specific forms 90 shown and described may be made within the scope of the claim without departing from the spirit of my invention.

I claim:

The combination of a unit having a pocket 95 formed therein, said pocket having a relatively enlarged inner end portion, a pliable lining in surface engagement with the walls of said pocket and conforming to the shape thereof, a second unit contiguous to the first 100 member and provided with a groove, a sealing member bridging the joint between said units and extending into said pocket between and in surface engagement with the lining therein, the inner edge of said member being located within the enlarged portion of 105 said pocket, an edge member extending from said sealing member into said groove in en-

gagement with one wall thereof and a flange extending at an inclination from said edge member into engagement with the opposite wall of said groove whereby a withdrawal of 5 said edge member from said groove is resisted.

In testimony whereof I have hereunto set

my hand in the presence of two subscribing witnesses.

AUGUST W. CORDES.

Witnesses:
